RAIL ANCHOR

George Loop Moore and James Robert Steele,
Owego, N. Y.

Application January 14, 1939, Serial No. 250,866

12 Claims. (Cl. 238—315)

Our invention relates to rail anchors and particularly to anchors for resisting the creeping of railroad rails in either direction of traffic.

One of the objects of our invention is to provide an anchor which is easily applied to a rail, which efficiently grips the rail and which cooperates with a member of the road bed to effectively retain the rail against displacement when the rail is in its assembled condition.

Another object of our invention is to provide a rail anchor which will check the longitudinal creeping of the rail in either direction of traffic.

A further object of our invention is to provide a rail anchor which is adaptable to be inserted adjacent the fishing surface of the rail.

The novel features of our invention will be more fully understood from the following description and claims taken with the drawings in which—

Figure 1 is a sectional view of a railway track structure with one type of our improved rail anchor partly installed therewith;

Fig. 2 is a top plan view of the anchor shown in Fig. 1 assembled with the track structure;

Fig. 3 is an end view of the anchor shown in Fig. 1 in its assembled relation with the track structure;

Fig. 4 is a side view in elevation of the anchor in its applied position;

Fig. 5 is a sectional view of a railway track with one of our modified anchors assembled therewith;

Fig. 6 is a sectional view of a railway track structure with two of our anchors in their assembled position therewith; and

Figs. 7, 8, 9 and 10 are views similar to Figs. 1, 2, 3 and 4, respectively, showing another modification of our invention.

Referring to Figures 1 to 4 of the drawings wherein we show a section of a railway track structure comprising a tie plate 15 mounted on the tie 16, and a rail 17 which is retained in position thereon by suitable fasteners including a member of our novel anchor which comprises the special spike or fastener 18 and the spring plate member 19. The fastener 18 in its preferred form comprises a shank portion 20 which is formed to fit tightly in the hole 14 in the tie plate 15 so as to completely fill the hole 14 when it is assembled with the structure and a head 21 having a vertical face 22 which as shown is perpendicular to the bottom surface of the base of the rail and side faces 23 and 24, respectively. The member 19 comprises a rail head engaging portion or flange 25, a bowed body portion 26, an arcuate portion 27, and a base flange engaging portion

28. A recess 30 is provided in the flange 28 to receive the spike head 21 to prevent the movement of the member 19 longitudinally of the rail 17, the vertical face 31 and the side faces 32 and 33, respectively, being formed so that they will engage the inner face 22 and the side faces 23 and 24, respectively, of the spike 18, when the member 19 is in its assembled condition with the track structure, and provide a substantially tight fit therebetween, as shown in Figure 3, so that the anchor is prevented from twisting to any substantial degree when a load is transmitted thereto.

The anchor 35 shown in Figure 5 is similar to that shown in Figures 1 to 4, inclusive, except that the face 36 adjacent the spike receiving recess is substantially perpendicular to the upper surface of the base flange of the rail and the spike head 37 is provided with a bevel face 38 which is at the same angle to the upper surface of the base flange of the rail as the face 36 so that when the anchor is in its assembled condition the member 35 will exert a downward pressure on the head 37 of the spike and therefore prevent the spike from lifting out of the tie. This structure provides a resilient anchor which permits the rail to undulate while at the same time effectively retains the spike against vertical displacement.

The anchor shown in Figures 7 to 10, inclusive, is similar to the anchors already described except that the lower flange of the resilient member is modified. This anchor comprises a spike 41 having a special head 42 to engage the base flange of the rail 17 and a resilient member 43 which is provided with a rail head engaging portion or flange 44, a bowed body portion 45, an arcuate portion 46 and a flange 47 having a recess 48 therein to receive the head 42 of the spike 41. The head 42 of the spike is provided with ears 49 and 50 which are engaged by the portions 52 and 53 of the flange 47. These ears 49 and 50 also serve for pulling the spike. The face 54 of the flange 47 engages the inner face 55 of the spike 41. This structure also provides a resilient anchor which permits the rail to undulate while at the same time it effectively retains the spike against vertical displacement and the rail from creeping in either direction of traffic.

The spikes used in connection with the resilient members are preferably made of carbon steel and heat treated so that they will retain the resilient members in their proper relation and effectively retain the rail against creeping in either direction.

In Figure 6 we show one type of our novel anchors assembled with a rail, the resilient members having been sprung at A and B, respectively, during assembly. Referring to the resilient member in the left fishing space of the rail, which is so made that where M is the moment, and $F-F$ equals the resultant reaction of the upward forces and the downward forces, respectively, of the resilient member and the upward force F is at a greater distance from the web of the rail than the downward force F , the difference being indicated by the letter S , and D equals the distance between the points $FR-FR$, $MF-F$ tends to rotate the member into fishing of rail and the force with which it does this is equal and opposite to R and

$$FS = RD$$

$$R = \frac{S}{D} F$$

S = approximately $\frac{1}{4} D$ for average rail
 $\therefore R = \frac{1}{4} F$

It is apparent from the foregoing that the resilient member 19, which comprises a spike head engaging portion 31, a rail base engaging portion 28, a rail head engaging portion 25, an intermediate bowed body portion 26 and an arcuate portion 27, during its assembly with the rail, after being placed in the position shown in Figure 1 with the recess 30 adjacent the head of the spike and force applied to its upper flange 25 in the direction of the arrow, will be deformed sufficiently to permit the portion 25 to pass beneath the rail head and the portion 31 to rotate about the spike head 42 until the rail base engaging portion 28 engages the upper surface of the rail base flange and the rail head engaging portion 25 to pass inwardly towards the web of the rail a substantial distance beyond the spike engaging portion 31 to the position shown in full lines in Figure 6. As stated before when the anchor is in its assembled condition with the rail the upward force F tends to rotate the rail head engaging portion 25 inwardly towards the web of the rail due to the member 19 tending to resume its normal or original condition, as shown in dotted lines in Figure 6, and as the downward force F is exerted in a plane which lies a substantial distance inwardly towards the web of the rail from the vertical plane passing through the point of exertion of the upwardly directed force F , a constant diagonal pressure is exerted between the upwardly directed force F and the downwardly directed force F which tends to force the railhead engaging portion further towards the web of the rail. As the diagonal distance between the points $FR-FR$ is greater than the distance D and as the tendency of the member 19 is to resume its normal condition in a direction diagonal with respect to the web of the rail towards the web of the rail, as shown in dotted lines Figure 6, there will be a constant tendency for the upper end of the anchor to move towards the web of the rail and thereby to effectively retain the anchor in gripping engagement with the rail.

As our novel anchor comprising a resilient member made of plate material allows quite a large deflection and coupled with this the fact that our anchor in its unsprung condition is as shown in dotted lines in Figure 6, when the anchor is in its sprung condition and the flange 23 is in contact with head of the rail and the upper end is in contact with the rail base flange, as shown in full lines in Figure 6, there is a constant tendency for the upper end of the anchor to move further toward the fillet when it is sub-

jected to load or vibration and therefore to effectively prevent the rail from creeping in either direction.

Referring to Figures 1 and 3 of the drawings 5 the anchor is assembled with the track structure by inserting the spike 18 through the tie plate 15 into the tie 16 thus fastening the rail 17 to the tie 16. The flange 28 of the anchor member 19 is placed on the upper surface of the rail base 10 flange with the faces 31, 32 and 33 engaging the faces 22, 23, and 24, respectively, of the head of the spike 18, as shown in Figure 1, and with the upper flange 25 disposed above the under surface of the head of the rail 17. The flange 25 is then 15 depressed downwardly and inwardly by suitable means, such as striking a blow thereon in the direction of the arrow, until the flange 25 passes beneath the head of the rail to the position shown in Figure 3. During this operation the bowed body portion 26 of the member 19 and the arcuate portion 27 have assumed the condition shown in Figure 3. In this condition the tendency of the member 19 is to assume the position shown in dotted lines in Figure 6 and to wedge the flange 25 further towards the fillet 40 of the rail. Due to the constant tendency of the arcuate portion 27 to resume its original condition there is a 20 tendency for the upper portion of the anchor to be constantly urged towards the fillet 40 and therefore there is no danger of the anchor becoming accidentally displaced in service.

The anchor member 35, as shown in Figure 5, 25 is assembled in the same manner as the anchor member 19 and operates in the same manner as that anchor, but in addition the bevel face 36 of the anchor member 35 engages the bevel face 38 of the head of the spike 37 and thereby exerts a downward pressure on the spike head and prevents the spike 37 from lifting out of the tie plate 30 although allowing the rail to undulate without affecting the efficiency of the anchor.

The anchor shown in Figures 7 to 10, inclusive, 35 is assembled with the track structure by inserting the spike 41 through the tie plate 15 into the tie 16. The flange 47 of the member 43 is placed upon the head of the spike 41 with the portions 52 and 53 resting on the ears 49 and 50, respectively, as shown in Figure 7 and with the upper flange 44 disposed above the under surface of the head of the rail 17. The flange 44 is then depressed downwardly and inwardly by suitable means such as striking a blow thereon in the direction of the arrow, until the flange 44 passes beneath the head of the rail to the position shown in Figure 10. During this operation the bowed body portion 45 and the arcuate portion 46 have assumed the condition shown in Figure 10. In this condition the tendency of the member 43 is to assume the position shown in dotted lines in Figure 6 and to wedge the flange 44 further towards the fillet 40 of the rail and therefore due to the constant tendency of the arcuate portion 27 to resume its original condition there is a tendency for the upper portion of the anchor to be constantly urged towards the fillet 40 and therefore there is no danger of the anchor becoming accidentally displaced in service as the member 43 effectively retains the spike 41 against vertical displacement.

By changing the bends in our anchors the required resistance for any predetermined load can be determined and should excessive loads be applied to the anchor it will slip until the load passes from above this predetermined amount, but as soon as the load is again normal

the anchor will immediately become effective to retain the rail against further creeping.

From the above it will be obvious that we have devised a rail anchor a member of which can be applied, removed and reapplied without the removal of the spikes, and one which permits the rail to undulate without losing its efficiency; also an anchor which is resilient so that it will effectively grip the rail a predetermined amount and absorb the shock but which will slip upon a load above the predetermined amount being imposed thereon so that its efficiency will not be impaired due to excessive loads, and which can be used on worn as well as new rails because of its resilient structure.

While we have shown our invention in a plurality of forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

Having thus described our invention, what we claim as new and desire to secure by Letters Patent is:

1. In a railway track structure, including a rail and a seat for said rail, an anchor retaining said rail in operative relation with said seat, said anchor comprising a spike and a resilient member of such form that it is incapable of being assembled with the rail in its normal condition and it is necessary to deform said member during its application to the rail, said member having a bowed body and flanged ends, one of said flanged ends engaging the upper surface of the rail base and having a recess therein receptive of the head of said spike and the other of said flanged ends engaging the under surface of the rail head, the central longitudinal plane normal to the engaged surface of the rail head lying inwardly of the outer edge of the rail base surface adjacent the spike head engaged by said flanged end receiving the spike head.

2. A resilient rail anchor to be applied to surfaces in the fishing space of a rail, said anchor being so dimensioned that it is incapable of assembly in its normal condition with said surfaces and it is therefore necessary to deform said anchor during its application with the rail comprising an end portion to engage the under surface of a rail head, an end portion to engage the rail base flange, an arcuate portion intermediate said end portions, and a spike engaging portion extending laterally from and integral with the rail base flange end portion, said rail head engaging portion and said rail flange engaging portion and said spike engaging portion being so dimensioned and related that when the anchor is in its effective assembled position with the rail the central longitudinal plane normal to the surface of the rail head engaged by the rail head engaging portion will lie inwardly of the outer edge of the rail base engaging portion adjacent the spike head engaging portion so that the reaction between said portions will cause the anchor to be retained in its effective gripping relation with the rail.

3. A resilient rail anchor comprising an end portion to engage the under surface of a rail head, an end flanged portion to engage the rail base flange, a body portion intermediate said end portions, an arcuate portion intermediate said body portion and the rail base engaging

end portion, and a spike engaging portion integral with the outer edge of the rail base engaging portion, said anchor in its normal condition being of a form that when the anchor is initially applied to the rail with the spike engaging portion in engagement with the spike head the rail head engaging end portion will lie a substantial distance above the plane of the under surface of the rail head to be engaged by said portion when the anchor is in its effective assembled condition and the major portion of the flanged end portion is out of engagement with the rail base flange and to assemble said anchor to its effective position it is necessary to apply pressure to said rail head engaging portion so as to force said portion beneath the rail head, thereby deforming said anchor about its arcuate portion and forcing the major portion of the end flanged portion into engagement with the rail base flange and the other end portion into its effective engagement with the under surface of the rail head; the longitudinal plane which is normal to and passes through the innermost portion of said surface and the rail head engaging portion lying inwardly of the spike engaging portion.

4. In a railway track structure, including a rail and a seat for said rail, an anchor for said rail, said anchor comprising a spike having a special head and a spring plate member in spaced relation to the rail seat having a bowed body adapted to be deformed during application of the anchor to the track structure and flanged ends, one of said flanged ends when the anchor is initially applied to the rail in its normal condition lying in a plane above the under surface of the rail head with which it is to be engaged in its effective assembled condition whereby during application of the anchor to its effective assembled position with the rail it is necessary to deform said anchor and permit said flange end to engage the under surface of the rail head and the other of said flanged ends adapted to engage the rail base flange and the head of the spike to retain said plate member and the spike in their assembled relation with the track structure.

5. A rail anchor comprising a resilient member adapted to be distorted to permit its entry into the fishing space of a rail, said member having a portion to engage the under surface of the rail head, a flange to engage the upper surface of the rail base flange and the head of the rail fastening spike at the edge of the rail, the central longitudinal plane normal to the surface of the rail head engaged by the rail head engaging portion lying inwardly of the outer edge of the flange engaging the rail base adjacent the spike head, and a body having an arcuate portion connecting said flanges.

6. A rail anchor adapted to be inserted into the fishing space of a rail, said anchor having a length before assembly greater than the width of the fishing space of the rail, said anchor comprising a resilient body portion and end portions, said body portion adapted to be deformed during the assembly of the anchor with the rail thereby permitting the anchor to enter the fishing space of the rail, and a spike head engaging portion having a recess adapted to receive a spike head when the anchor is in its assembled condition with the rail, said anchor, fishing space and spike head being so formed and arranged that the anchor, when initially applied to a rail with the spike head engaging portion in contact with the spike head, will have its upper end projecting a substantial distance above the entrance to

the fishing space of the rail and in the application of the anchor to its effective assembled position force is applied to the upper end thereof to deform the anchor and rotate it about the spike head towards the web of the rail until the rail head engaging portion passes a distance beyond the spike head engaging portion and engages the under surface of the rail head, said under surface lying in a plane substantially normal to the diagonal longitudinal plane passing through the innermost portion of the rail head engaging portion and the spike engaging portion.

7. A rail anchor having a lower surface adapted to engage the upper side of the base flange of the rail and a face adjacent the margin of said surface to engage the head of a track spike, an upper surface adapted to engage the underside of the head of the rail, the surface of which is so disposed with relation to the spike that the longitudinal plane normal to the innermost portion of said surface engaged by said upper surface of the anchor, when the anchor is in its effective position, lies inwardly of the spike, and a resilient portion intermediate said surfaces, the upper surface being so positioned with respect to said lower surface that when the anchor is initially applied to the rail with its lower marginal edge surface in contact with the base flange of the rail the said upper surface is adjacent the side face of the rail head in a plane considerably above the under surface of the rail head with which it is engaged after the anchor is applied in its effective position on the rail, whereby a downward force is necessary to sufficiently spring the resilient portion of the anchor to force the upper surface thereof beneath the rail head into its effective position on the rail.

8. A rail anchor having a lower surface adapted to engage the upper side of the flange of the rail base and an adjacent surface to engage the head of a track spike and an upper surface adapted to engage the under side of the head of the rail, and a resilient portion intermediate said surfaces, the upper surface being so positioned with respect to said lower surface that when the anchor is initially applied to the rail in its normal condition with its spike engaging surface adjacent the spike head the said upper surface is in a plane considerably above the under surface of the head of the rail with which it is to engage after the anchor is effectively applied to the rail and a considerable downward and inward force is necessary to deform said anchor sufficiently to permit the upper surface of the anchor to pass beneath the head of the rail and into its effective gripping relation with the under surface thereof, the central longitudinal plane normal to the engaged under surface lying inwardly of the outer edge of the portion of the anchor engaging the spike head.

9. A rail anchor having a lower surface adapted to engage the upper side of the flange of the rail and an upper surface adapted to engage the underside of the head of the rail and a resilient portion intermediate said surface, the upper surface being so positioned with respect to said lower surface that when the anchor is initially applied to the rail the said upper surface is in a plane above the surface of the rail with which it is engaged after the anchor is effectively applied to the rail whereby a downward and inner blow on the upper end of the anchor will deform said

resilient portion and spring the anchor into its effective position with the upper surface of the rail base flange, and under surface of the rail head, and a surface to engage a spike, the central longitudinal plane normal to the under surface of the rail head engaged by said anchor lying inwardly of the spike engaging surface, whereby the anchor is retained in its effective position on the rail by the pressure imposed on the engaging surfaces by the resilient portion tending to assume its original condition.

10. A rail anchor comprising a resilient member adapted to be distorted to permit its entry into the fishing space of a rail, said member having a rail head engaging portion to engage the under surface of the rail head, a rail base flange engaging portion to engage the upper surface of the rail base flange and to abut a member adjacent the edge of the rail, and a body portion connecting the head and flange engaging portions; the longitudinal plane normal to the surface of the rail head engaged by the rail head engaging portion which passes through the inner longitudinal edge of said rail head engaging portion lying inwardly of the outer edge of the rail base flange engaging portion which abuts a member adjacent the edge of the rail.

11. A resilient rail anchor to grippingly engage the fishing surfaces of a rail in its assembled condition, said anchor comprising a rail head engaging portion, a rail base flange engaging portion and an arcuate portion intermediate said rail head engaging portion and said rail base flange engaging portion, said anchor adapted to be distorted during its application to the fishing surfaces of the rail to permit the rail head engaging portion to pass beneath the rail head and into engagement with the under surface of the rail head in the fishing space of the rail and said rail base flange engaging portion adapted to abut a member adjacent the edge of the rail base flange to retain said anchor against displacement in its assembled condition; a longitudinal plane normal to the innermost under surface of the rail head engaged by the rail head engaging portion, and passing through said rail head engaging portion, lying inwardly of the outer edge of the flange engaging portion which abuts a member adjacent the edge of the rail base flange.

12. A resilient rail anchor to grippingly engage the fishing surfaces of a rail in its assembled condition, said anchor comprising a rail head engaging portion, a rail base flange engaging portion and an arcuate portion intermediate said rail head engaging portion and said rail base flange engaging portion, said anchor adapted to be distorted during its application to the fishing surfaces of the rail to permit the rail head engaging portion to pass beneath the rail head and into engagement with the under surface of the rail head in the fishing space of the rail and said rail base flange engaging portion adapted to abut a member adjacent the edge of the rail base flange to retain said anchor against displacement, said member lying outwardly of the longitudinal plane which is normal to the innermost surface of the rail head engaged by the rail head engaging portion.
